UNITED STATES PATENT OFFICE.

JAMES EVERITT, OF LONDON, ENGLAND.

CLOTHES-HANGING BAR FORMED OF HINGED-TOGETHER MEMBERS.

Application filed February 1, 1923. Serial No. 616,437.

To all whom it may concern:

Be it known that I, JAMES EVERITT, subject of the King of Great Britain, residing at 31 Kingly Street, Regent Street, London, 5 W. 1, in the county of London, England, manufacturer, have invented certain new and useful Improvements in a Clothes-Hanging Bar Formed of Hinged-Together members, of which the following is a specification.

The invention has reference to a clothes hanging bar of the type formed by two hinged together members the one of which is fixed and the other arranged to swing up 15 and down from the one end to constitute a rigid length at one time upon which runners can ride, and at another time reduce the length with all the runners suspended from the fixed member.

20 The invention provides a special construction and operation of catch for holding the members rigidly together as one rigid length and for enabling the one to swing downwardly upon the other to fold said length.

25 Said catch comes automatically into action to hold the members as a rigid length by the simple act of swinging the one member upon the other member, and is hand operated out of action, and the essential features 30 of it are a projection or lug having an inclined upper edge and a declining rear edge, and a swingable link to co-act with this projection or lug, the latter being applied to the one member and the swingable link to the other member. Preferably the projection or lug is attached to the top of the 35 fixed member, and the swingable link pivoted to the swinging down member.

40 The declining rear edge operates in conjunction with the link so that the two members are held to each other end to end to constitute a single length without any looseness.

45 The invention also includes constructional features by which two opposite projections or lugs are provided, and the link is in the form of an elongated loop of stout wire, and also an external shoe to provide the point of hinging of the two members to 50 each other and to strengthen such hinging and to hold the members so that they line up exactly in a transverse direction when held together to form one rigid length, this shoe also providing a convenient feature for 55 the attachment of the lugs or projections and for a bracket whereby this end of the fixed

member is secured to the top of a wardrobe interior.

A puller out device to the runners can be conveniently provided.

The invention is represented by the accompanying drawings.

Fig. 1 is a top-side plan of the fitting extended to form one rigid length.

Fig. 2 is an underside plan of Fig. 1.

Figs. 3 and 4 are a side view and a plan of the link separately.

Fig. 5 is a side elevation of Fig. 1, but also showing by dotted lines the hinged member swung downwardly.

70 Figs. 6 and 7 show a side elevation and a plan of a part constituting the two projections or lugs, one of the attachment brackets, and a stop to prevent the free end of the link falling away from the projections or lugs 75 when the hinged member swings down.

The tubular fitting is composed of two tubular members *a* and *c* hinged together at *d*. Both members are of substantially square cross section but provide a central longitudinal slot *e* throughout their under wall so that runners *f* projecting through the slots may ride within the interior of both tube members and pass quite freely the point where said members are hinged to each other; these features all being known.

75 The tubular member *a* is rigidly secured to the back and top of a wardrobe interior by the brackets *a*², *a*³ and the tubular member *c* is adapted to swing up and down upon *a*, about the point of hinging *d*, to at one time constitute a single rigid length of tube as shown in Figs. 1, 2 and 5, and at another time fold as shown by the dotted lines *x*, Fig. 5, to reduce the length and enable the 85 wardrobe door to shut.

80 To strengthen the hinging of the two tubular members, and to cause them to line up truly, particularly transversely, an external shoe *h* is rigidly attached to the fixed member so that the folding member swings within its one end *h*², this shoe admitting 90 free passage of the runners *f*.

95 The catch which is the particular feature of the invention is provided by the pair of projections or lugs *i* and the pivoted link *g*. Said lugs form part of a metal piece providing the bracket *a*³ and which is rigidly attached to the top of the fixed shoe *h*. Said projections or lugs are a pair, and each is 105 the same shape and has an inclined upper edge *i*² and a declining rear edge *i*³, the up-

per edge declining forwardly from the rear edge, and the rear edge slightly declining rearwardly from the upper edge. The pivoted link co-acts with these edges, aforesaid, particularly the rear edge i^3 , and constitutes a coupling piece between the hinged member c and the lugs.

Said pivoted link is in the form of an elongated loop made from stout wire, its one end g^2 being pivoted to the hinged member c and its other and free end g^3 adapted to co-act with the projections or lugs i , which are a distance apart and operative within the loop.

At the pivoted end of this link a hand lever g^4 is fitted for operation to lift the free end g^3 of the link clear of the declined back edges i^2 of the projections or lugs, so that the hinged member c may swing down or fold to the position represented at α in Fig. 5.

The declining edges i^3 co-act with the free end of the link so that when they engage, as shown in Figs. 1, 2 and 5 the hinged member c is pulled up tight into the shoe h , and so held without any looseness, the sides of the shoe holding this joint transversely against looseness.

When the hinged member c is folded as at α the free end of the link g is held from too far falling away from the projections or lugs i by the stop y which is formed as a part of the metal piece providing said projections or lugs and the bracket a^3 , this stop y touching the top of the wardrobe space.

When the hinged member c is swung upwardly from the dotted position α the free end g^3 of the link will first ride up the inclined edges i^2 and will afterwards fall down the edges i^3 to effectively hold the two tubular members a and c in line as one tubular length, when the runners f can be slid along the full length and the garment sorted out and removed.

It is quite convenient to apply a puller out device to the tubular fitting; same is shown in the form of a rod length j extending along the top of the fixed member a between the projections or lugs i and through the bracket a^3 , the front end j^2 of this rod being fashioned into a handle, and

the rear end j^3 being attached to a dummy runner l sliding along the tubular member at the back of all the runners f .

Having now described my invention what I claim and desire to secure by Letters Patent is:—

1. A clothes hanging bar, combining a fixed and a hinged member suitable for runners to travel upon, a projection having an inclined upper edge and a declining rear edge rigidly applied to the upper surface of the fixed member, and a pivoted link applied to the swingable member to co-act with the upper and rear edges of the projection for holding the swingable member in end to end alignment with the fixed member and adapted for hand operation, substantially as described.

2. A clothes hanging bar, combining a fixed and a hinged member suitable for runners to travel upon, a pair of projections having inclined upper edges and declining rear edges rigidly applied to the fixed member, and a pivoted link in the form of an elongated stout wire loop hinged by one end to the swingable member and adapted by its other end to engage the pair of projections for holding the members in end to end adjustment with each other, substantially as described.

3. A clothes hanging bar, combining a fixed tubular member and a hinged tubular member suitable for runners to travel upon, said members being hinged together, a shoe at the end of said fixed member to assist the hinging movement of the hinged member, a projection having an inclined upper edge and a declining rear edge rigidly applied to the fixed member, and a pivoted link applied to the swingable member and adapted to cooperate with the rear edge of the projection for holding the hinged member in end to end alignment with the fixed member, said link being adapted to be moved out of action by hand and to be moved into action automatically by its own weight, substantially as described.

In testimony whereof I have hereunto set my hand.

JAMES EVERITT.
